UNITED STATES PATENT OFFICE.

LOUIS P. KOVANDA AND JAY H. HUBBELL, OF LOS ANGELES, CALIFORNIA.

METHOD OF LINING CONCRETE SEWERS, DUCTS, AND CONTAINERS.

Application filed December 16, 1925. Serial No. 75,694.

Our invention relates to a method of lining concrete sewers, ducts, and containers, and has for its principal object the provision of a relatively simple and easily practiced method of providing ducts and containers that are formed of concrete or like material with an acid-proof lining in order that the inner surface of the duct or container will be thoroughly protected against the action of deleterious liquids, gases, and the like.

It will be understood that where it is desired to protect the inner surfaces of concrete sewers and the ducts and containers for certain liquids against the destructive action of certain gases and liquids, it is the present general practice to line the concrete structures with vitrified clay tile or blocks and to render such lining thoroughly acid-proof, it is necessary to fill the joints between the lining tiles or blocks with some acid-proof material. If the joints between the lining tile or blocks are not filled with some inert material, the concrete back of the joints and lining blocks will be attacked by destructive acids and gases through the joints and in a short time the lining members will become loose and drop from their place in the structure, thereby not only exposing the concrete body of the sewer or container to the destroying elements, but also obstructing the free flow of sewage or liquid through the duct or sewer.

To fill the joints between the vitrified clay lining tile or blocks with an inert acid-proof material is impractical from an economical standpoint inasmuch as the filling of such joints involves considerable time, labor, material, and consequent expense.

It is one of the purposes of our invention to simplify and cheapen the cost of construction of lined concrete structures and to do away with the necessity of the expensive and practically useless segmental vitrified clay lining tile or blocks now generally used in the construction of sewers and the like and to accomplish our object we propose to provide a continuous and jointless lining of acid-proof materials for ducts and containers that are formed of concrete and which continuous lining is of such nature as to afford complete protection for the concrete against the destructive action of sewage,

gases, liquids and the like, and which latter are highly detrimental to the life of the concrete where the latter is not protected.

A further object of our invention is to provide a protective lining and method of applying same whereby said lining forms an integral part of the structure so that it will not flake, disintegrate and fall off as would be the case if lining materials such as asphaltic or tar paints were used.

With the foregoing and other objects in view our invention consists in certain features of novelty hereinafter more fully described and claimed and illustrated in the accompanying drawings, in which—

Fig. 1 is a perspective view of a concrete sewer in the process of construction and the upper or arch portion of which is lined in accordance with our improved method.

Fig. 2 is a cross sectional view of the completed sewer with the lining applied thereto.

Fig. 3 is a perspective view of a form for producing pre-cast sewer pipe and which latter is lined with the continuous acid-proof material in accordance with our invention.

Fig. 4 is a sectional view showing the method employed in bonding parts of our improved lining to one another.

Fig. 5 is a detailed section of a portion of a joint between sections of pre-cast sewer pipe and showing the arrangement of the lining therein.

In lining monolithic sewer structures of the type described in Figs. 1 and 2, the sheet metal forms 10 for producing the upper or arched portion of the sewer are arranged in the channel portion of the invert or base 11 of the sewer and before the concrete that forms the upper or arched portion of the sewer is applied to the arched form 10, the upper or outer surface of said form 10 has applied thereto in any suitable manner a layer 12 of inert acid-proof material, preferably a compound consisting of approximately 50% sulphur and 50% fine sand well graded to give maximum strength.

This lining compound is placed on the form while in molten condition and we have found that said lining material can be very quickly and evenly distributed on the form by spraying the same from a molten material spraying apparatus of the type disclosed

in our copending application for U. S. Letters Patent filed October 1, 1925, Serial No. 59,821.

The molten material when sprayed onto the form 10 sets very quickly and thus the entire lining is practically one homogeneous mass in the form of a layer or sheet of substantial thickness and entirely devoid of joints. At the end of a working period the 10 edge of the molten lining material sprayed onto the form 10 is tapered or beveled off as designated by 13 in Fig. 4, and when the work of applying the lining compound is continued, the molten material applied from 15 the spraying apparatus will soften the tapered portion 13 previously applied to a sufficient degree to form a perfect joint thus eliminating joints and making the entire lining practically continuous.

20 After the acid-proof lining has been thus applied to the form 10 the upper or arched portion 14 of the sewer structure is applied directly over the lining and the concrete forming the arch portion of the sewer and 25 the lining 12, both being composed wholly of mineral substances, will produce a perfect bond so that the lining is practically an integral part of the sewer body.

In Figs. 1 and 2 we have shown the upper 30 or arched portion only of the sewer as being provided with the acid-proof lining contemplated by our invention, but it will be understood that if desired the lining material may be applied to the surface of the 35 channel in the base or invert 11 thereby affording complete protection for all portions of the inner surface of the sewer.

When our improved lining is applied to 40 pre-cast sewer pipe, the outer surface of a tubular or cylindrical form 15 is covered or coated with the lining material while the latter is in molten condition and when said material has become set the coated form is 45 concentrically arranged within an outer tubular form 16 and the concrete body 17 of the sewer pipe is poured into the space between the outer form and the coated inner form. When the concrete has become set 50 and hard the forms are removed and thus lined sewer pipe section is produced.

In the event that the lining is applied to 55 pre-cast sewer pipes having bell or flanged ends, the linings terminate short distances from the ends of the pipe sections as shown in Fig. 5, and when pipe sections are assembled, the annular grooves between the ends of the linings are filled with molten lining material, thereby providing a practically continuous acid-proof lining.

60 In the event that a concrete sewer or duct is laid in soil that contains alkali or other agent that might act on the concrete with injurious results, the entire exterior surface of the sewer or duct may be given a protective coating of the sulphur-silica compound,

the latter being applied in any suitable manner, preferably by spraying.

Thus it will be seen that we have provided a relatively simple, practical and economical method of providing sewers, ducts and containers with an acid-proof lining that affords complete protection for the concrete body of the structure against the deleterious and destructive action of sewage, gases, liquids and the like, and which lining is practically continuous and forms an integral part of the structure with which it is associated.

We claim as our invention:

1. The herein described method of providing concrete ducts and containers with acid-proof linings which consists in applying an inert acid-proof compound to a form while in plastic condition and when said lining material has become set, applying thereto the concrete that forms the body of the completed structure.

2. The herein described method of lining monolithic sewers, ducts, and containers, which consists in applying to a form a layer of molten acid-proof material and when said molten material has become set, applying thereto the concrete that forms the body of the monolithic structure.

3. The herein described method of providing concrete sewers, ducts, and containers, with an acid-proof lining which consists in producing a layer of acid-proof material that corresponds to the form of the inner surface of the completed structure and then applying to said layer of acid-proof material the concrete that forms the body of the completed structure.

4. The herein described method of providing monolithic sewers and containers with acid-proof linings which consists in shaping a molten silica-sulphur compound to correspond with the form of the inner surface of the monolithic structure and then applying to the formed silica-sulphur lining structure the concrete that forms the body of the completed structure.

5. The herein described method of rendering the inner surfaces of concrete ducts and containers acid-proof which consists in forming a lining layer of inert acid-proof material while the same is in plastic condition and when said lining layer has become set, applying thereto the concrete that forms the body of the completed structure.

6. The herein described method of rendering the inner surfaces of concrete ducts and containers acid-proof which consists in forming a lining layer of sulphur-silica compound while the same is in molten condition and when said lining layer has become set, applying thereto the concrete that forms the body of the completed structure.

7. The herein described method of lining monolithic ducts and containers which con-

sists in applying to a form a lining layer of sulphur-silica compound while the same is in molten condition and when said lining layer has become set, applying thereto the concrete that forms the body of the completed monolithic structure.

8. The herein described method of lining monolithic ducts and containers which consists in applying to a form a jointless homo-

geneous lining layer of sulphur-silica compound while the same is in molten condition and when said lining layer has become set, applying thereto the concrete that forms the body of the complete monolithic structure.

In testimony whereof we affix our signatures.
